UNITED STATES PATENT OFFICE

120,918

DESIGN FOR A PARKING LAMP OR SIMILAR ARTICLE

Arthur R. Pass, Toledo, Ohio, assignor to The Toledo Automotive Products Co., Toledo, Ohio, a corporation of Ohio

Application March 12, 1940, Serial No. 90,856

Term of patent 7 years

To all whom it may concern:

Be it known that I, Arthur R. Pass, a citizen of the United States of America, residing at Toledo, Lucas County, Ohio, have invented a new, original, and ornamental Design for a Parking Lamp or Similar Article, of which the following is a specification, reference being had to the accompanying drawing, forming part thereof:

Fig. 1 is a side elevational view of a parking lamp showing my new design;

Fig. 2 is a front elevational view thereof; and Fig. 3 is a rear elevational view thereof. The dominant feature of my design resides in the parts shown in full lines.

I claim:

The ornamental design for a parking lamp or similar article, substantially as shown and described.

ARTHUR R. PASS.
